UNITED STATES PATENT OFFICE

CHARLES S. DUTTON, OF OAKLAND, EGBERT ALEXANDER, OF SAN FRANCISCO, AND GEORGE H. DERRICK, OF OAKLAND, CALIFORNIA; VICTORY A. DERRICK, EXECUTRIX OF SAID GEORGE H. DERRICK, DECEASED, ASSIGNEES, BY MESNE ASSIGNMENTS, TO INSTOGRAPH, LTD., A CORPORATION

MAKE-AND-BREAK MECHANISM FOR ELECTRIC SWITCHES

Application filed December 7, 1925. Serial No. 73,535.

The present invention relates to improvements in make and break mechanism for electric switches and its particular object is to provide a device of the character described by which movement of the printing wheel of a stamping device may be caused to synchronize with movements of a clock mechanism so that numerals arranged on the printing wheel always show the correct time at the exposed 10 surface.

It is further proposed to arrange the make and break mechanism in such a manner that the opening of the switch takes place instantaneously after the closing thereof.

Further objects and advantages of our invention will appear as the specification proceeds.

The preferred form of our invention is illustrated in the accompanying drawing in 20 which

Figure 1 shows a top plan view of our mechanism.

Figure 2 a front view thereof.

Figure 3 a side view of the same.

While we have shown only the preferred form of the invention it should be understood that various changes or modifications may be made within the scope of the claims hereto attached without departing from the spirit of 30 the invention.

The shaft 1 emanates from a clock mechanism not shown in the drawing and the shaft 2 has a printing wheel fixed thereto which latter also is not shown in the drawing.

The object of the present invention being 35 to cause an electrical impulse to be imparted to the shaft 2 causing it to synchronize with the rotary motion of the shaft 1 of the clock mechanism. Power for revolving the shaft 2 is supplied by the electro-magnet 3 which has an armature 4 pivoted relative thereto as shown at 6. A link 7 is pivoted to the free end of the armature as at 8 and has a tooth 9

projecting therefrom which latter is adapted 40 for engagement with the teeth of a toothed wheel 11 fixed on the shaft 2. When the electro-magnet is energized the armature is attracted and causes the link 7 to move upwardly, which also forces the link outwardly 45 due to the slanting faces of the meshing

teeth. This outward movement of the link 7 is opposed by a spring 12 which latter serves to force the tooth on the link inwardly as soon as the same has passed the crest of the wheel tooth responsible for its outward movement. The upward stroke of the link 7 is preferably made to exceed the length of a tooth so that positive engagement of the link tooth with the next wheel tooth is always assured before the link is moved in the opposite direction for advancing the wheel 11 by the length of one tooth. Reversal of the movement of the link 7 is brought about by the automatic opening of the switch 13 by means 55 to be described hereinafter and the spring 14 which opposes the motion of the armature and forces the latter away from the magnet as soon as the latter becomes de-energized. The wheel 11 preferably has sixty teeth thereon and the electro-magnet is energized sixty 60 times in an hour so that each advance movement of the wheel 11 means the passing of one minute.

The make and break mechanism for the 65 switch 13 includes a ratchet wheel 16 on the shaft 17 which latter is revolved by the shaft 1 through the gear wheel 18 and the pinion 19 in such a manner that the ratchet wheel advances by the length of one tooth per minute. The direction of rotation is clockwise 70 as shown in Figure 2, the switch comprising a stationary contact 21 and a movable contact 22 mounted at the end of a leaf spring 23 one end of which is fixed to a block 24 of insulating material. An intermediate portion of the spring near the contact 22 is opposed by a lug 26 projecting laterally from the free end of the lever 27, pivoted at a distance from the stationary 75 contact 21 as shown at 28. The lever arm just mentioned extends upwardly and has pivoted to its upper end, as shown at 29 a link 31 provided with a tooth 32 adapted to engage with and rest on any one of the teeth of the toothed member 16, a leaf spring 33 tending to crowd the tooth of the link into engagement with the teeth of the ratchet. 80 is gradually forced out of the outer periphery as viewed in Figure 2 the tooth of the link 85 As the ratchet revolves in clockwise direction 90

ery of the ratchet, hence and since the tooth 32 is the only support for the lever 27 the latter drops while the link 31 rides downwardly over the teeth of the ratchet and allows the spring switch 23 of which this contact 22 is a part to move downwardly bringing into engagement contact 22 with the contact 21 whereby the switch is closed.

The closing of the switch energizes the electro-magnet 3 and brings about the end-
wise motion of the link 7 previously referred to. While the link 7 climbs upwardly and is forced outwardly by the slanting face of the tooth engaged by the same, its upward end just clears a finger 34 projecting from a lever 27 so as to assume the position as indicated in dotted lines in Figure 2 when the tooth 9 passes the top of the wheel tooth engaged by it. After the link tooth has passed the wheel tooth it is forced inwardly again by the action of the spring 12 for engagement with the next tooth and during this inward motion of the link 7 its upper end forces the finger 34 of the lever 27 inwardly thereby turning the entire lever about its pivot 28 and lifting the link 31 sufficiently to cause its tooth 32 to engage with the next ratchet tooth while at the same time the switch opened by the lug 26 raises the spring switch 23. To prevent any tendency of the ratchet to revolve in the opposite direction due to the fact that the link 31 rides upwardly on the teeth during the switch opening movement we provide a pawl 38 which engages with the pinion 19 and is positioned to drop behind a new tooth prior to the upward movement of the link 31.

The operation of the device is as follows: The shaft 1 revolved by a clock mechanism not shown transmits rotary motion through the gear wheel 18 and the pinion 19 to the shaft 17 in such a manner that the toothed wheel or ratchet 16 on the said shaft rotates by the length of one tooth per minute. As the ratchet revolves the tooth 32 on the link 31 which rests on one of the teeth of the ratchet is gradually forced outwardly by the next tooth and finally at the end of the minute is knocked off so that the link rides downwardly on the wheel and allows the lever 27 to drop and the switch 13 to close.

The closing of the switch energizes the electro-magnet 3, attracts the armature thereto which causes the link 7 to rise. During this rising motion the tooth 9 riding on the slanting face of one of the teeth of the wheel 11 is forced outwardly until it passes the point of the tooth and this upward and outward motion of the link 7 brings its upper end into the dotted line position for engagement with the finger 34. After having passed the point of the tooth on the wheel 11 the tooth 9 is allowed to go

inwardly again and this inward motion causes the upper end of the link to turn the lever 27 about its pivot whereby the switch 13 is opened. This inward motion further brings about an engagement of the link tooth 9 with the next tooth on the wheel 11. The opening of the switch de-energizes the electro-magnet 3 and the armature is forced away from the magnet by the spring 14 which movement causes the lever 7 to revolve the wheel 11 by the length of one tooth. It will be seen that in this manner the switch is closed once every minute, and opened again, which opening brings about a corresponding turning motion of the wheel 11 which latter is provided with sixty teeth so that it carries out a complete revolution in one hour.

It is understood that while the preferred impulse is sixty times per hour the intervals may be varied to give the electrical impulse at intervals of very much greater or very much less frequency either regular or irregular in spacing, and the ratio of desired action to actual established contact made by the spring switch may be varied to any desired degree.

We claim:

1. In combination, a rotating ratchet wheel, a stationary switch contact, a movable switch contact in operative relation to said stationary contact; an electro-magnet, means for actuating said movable contact, said means being held by said ratchet wheel, and released by the rotation of said wheel; said movable contact engaging said stationary contact upon the release of said means, thereby energizing said electro-magnet, means actuated by the energized electro-magnet for opening said switch, and means to transmit the movement of the electro-magnet, to a driven shaft, said means being actuated by the return movement of said switch opening means when said magnet is de-energized.

2. In combination, a rotating ratchet wheel, a stationary switch contact, a movable switch contact in operative relation to said stationary contact; an electro-magnet, resilient means for actuating said movable contact, said means being held by said ratchet wheel, and released by the rotation of said wheel; said movable contact engaging said stationary contact upon the release of said means, thereby energizing said electro-magnet, resilient means actuated by the energized electro-magnet for opening said switch, and means to transmit the movement of the electro-magnet, to a driven shaft said means being actuated by the return movement of said switch opening means when said magnet is de-energized.

3. In combination, a rotating wheel having notches on the periphery thereof, a stationary switch contact, a movable switch contact, means to connect said movable contact

with a notch of said wheel to be held in open position thereby; said means closing said switch upon the rotation of said notched wheel; an electro-magnet energized by the closing of said switch, means actuated by the movement of the electro-magnet when energized, to bring said connecting means in engagement with another notch on said wheel, thereby opening said movable switch contact, means for returning said electro-magnet actuated means when the opening of said movable contact causes the electro-magnet to be de-energized, and means for transmitting the movement of said electro-magnet, to a driven shaft said last means being operated by the returning movement of said magnet actuated means, in synchronism with the rotation of said notched wheel.

4. In combination, a rotating ratchet wheel, stationary switch contact, a movable switch contact in operative relation to said stationary contact; an electro-magnet, means for moving said movable contact, said means being held by the ratchet wheel and being lowered by the rotation of said wheel so as to lower said movable contact upon the stationary contact, for energizing the electro-magnet; a link pivoted to the free end of a resiliently mounted armature of said electro-magnet and having a tooth projecting therefrom; a toothed wheel adapted to rotate a transmission shaft and being disposed in operative relation to said tooth of the link; said link being moved upwardly and outwardly by the armature when the electro-magnet is energized so as to bring said tooth thereon in engagement with a successive tooth of the toothed wheel; and resilient means for causing said link to separate said contacts at the end of the upward movement of the link, thereby causing the de-energizing of said electro-magnet and the return movement of said link, thus turning said toothed wheel.

5. In combination, a rotating ratchet wheel, a stationary switch contact, a movable switch contact in operative relation to said stationary contact; an electro-magnet, a pivoted lever for moving said movable contact into and out of engagement with said stationary contact, means for connecting said lever to the ratchet wheel, said means being lowered by the rotation of said wheel so as to lower said movable contact upon the stationary contact for energizing the electro-magnet; an armature of said electro-magnet being resiliently mounted thereon; a link pivotally secured to the free end of the armature and having a tooth protruding therefrom; a toothed wheel adapted to rotate a transmission shaft and being disposed in operative relation to said tooth of the link so as to allow the engagement of a successive wheel tooth by said link tooth when said link is moved upwardly and outwardly by the action of the energized electro-magnet; and resil-

ent means for causing said link to raise said lever and said connecting means, the link tooth turning the toothed wheel when the link is moved downwardly by the armature of the de-energized electro-magnet.

6. In combination, a rotating ratchet wheel, a stationary switch contact, a movable switch contact in operative relation to said stationary contact; an electro-magnet, a pivoted lever for moving said movable contact into and out of engagement with said stationary contact, means for connecting said lever to the ratchet wheel, said means being lowered by the rotation of said wheel so as to lower said movable contact upon the stationary contact for energizing the electro-magnet; an armature of said electro-magnet being resiliently mounted thereon; a link pivotally secured to the free end of the armature and having a tooth protruding therefrom; a toothed wheel adapted to rotate a transmission shaft and being disposed in operative relation to said tooth of the link so as to allow the engagement of a successive wheel tooth by said link tooth when said link is moved upwardly and outwardly by the action of the energized electro-magnet; a finger on the free end of the link; and a spring for pressing said finger into engagement with the end of the pivoted lever after the upward and outward movement of the link, thereby raising said lever in a switch opening position; the link tooth turning the toothed wheel when the link is moved downwardly by the armature of the de-energized electro-magnet.

7. In combination a rotating ratchet wheel, a pivoted lever, a link pivotally related to the free end of the lever and engaging the teeth of the ratchet wheel, a stationary contact, a movable contact supported by the free end of the lever and above the stationary contact, an electromagnet, an armature pivotally related to the magnet at one of its ends, a link pivotally related to the armature at the other of its ends, a toothed wheel, a tooth carried by the link capable of slidable engagement with the teeth of the wheel, a spring for urging the link inwardly of the teeth of the wheel, a lug lying in the path of the inward movement of the link for rocking the free end of the lever upwardly upon its pivot.

8. In combination a rotating ratchet wheel, a pivoted lever, a link pivotally related to the free end of the lever for engaging the teeth of the ratchet wheel, a spring for urging the link into engagement with the ratchet wheel, a stationary contact, a movable contact supported by the free end of the lever and above the stationary contact, an electromagnet, an armature pivotally related to the magnet at one of its ends, a link pivotally related to the armature at the other of its ends, a toothed wheel, a tooth carried by the link

and capable of slidable engagement with the teeth of the wheel, a spring for urging the link inwardly of the teeth of the wheel, a lug carried by the lever and lying in the path of the inward movement of the link for rock-
5 ing the free end of the lever upwardly upon its pivot.

9. In combination a rotating ratchet wheel, a pivoted lever, a link pivotally related to the free end of the lever for engaging the teeth
10 of the ratchet wheel, a spring for urging the link into engagement with the ratchet wheel, a stationary contact, a movable contact sup-
ported by the free end of the lever and above
15 the stationary contact, an electromagnet, an armature pivotally related to the magnet at one of its ends, a link pivotally related to the armature at the other of its ends, a toothed wheel, a tooth carried by the link and capa-
ble of slidable engagement with the teeth of
20 the wheel, a spring for urging the link in-
wardly of the teeth of the wheel, a lug carried by the lever to one side and below the pivotal point thereof and lying in the path of the
25 inward movement of the last mentioned link for rotating the lever upon its pivot.

In testimony whereof we affix our sig-
natures.
